UNITED STATES PATENT OFFICE.

HENRY KUNTZ, OF TIFFIN, OHIO.

WHEEL CLEANER.

Application filed February 25, 1927. Serial No. 170,910.

This invention aims to provide a scraper which may be used on the wheel of a grain drill to clear the wheel of mud. One object of the invention is to provide a device 5 of the class described, which will permit the wheel to rotate, under ordinary conditions, without increased friction resulting from the application of a wheel cleaner to the wheel. Another object of the invention is 10 to provide novel means whereby the device may be attached to a grain drill of known and standard construction. Another object of the invention is to strengthen and reinforce the blade which operates immediately 15 to take the mud off the wheel.

It is within the province of the disclosure to improve generally and to enhance the utility of devices of that type to which the invention appertains.

20 With the above and other objects in view which will appear as the description proceeds, the invention resides in the combination and arrangement of parts and in the details of construction hereinafter described 25 and claimed, it being understood that changes in the precise embodiment of the invention herein disclosed may be made within the scope of what is claimed, without departing from the spirit of the invention.

30 In the drawings:—

Figure 1 shows in rear elevation, a grain drill equipped with the device forming the subject matter of this application;

Figure 2 is a top plan of the structure 35 shown in Figure 1;

Figure 3 is a side elevation of the structure shown in Figure 1.

The numeral 1 marks a grain drill including an axle 2 carrying a ground wheel 3. 40 The grain drill 1 comprises a rearwardly extended frame 4 on which the colters 5 and other parts of the seeding mechanism are supported. The frame 4 includes a cross bar 6, the ground wheel 3 extending rearwardly beyond the cross bar, at one end of the cross bar, as Figure 2 of the drawings will show.

The wheel cleaner is made of metal throughout, and includes a body 7 in the 45 form of a straight bar provided at one end with an arm 8 located at right angles to the body 7, the arm 8 having a finger 9 dis-

posed parallel to the body 7, the finger 9 and the body 7 projecting in opposite directions, from opposite ends of the arm 8, the parts 55 7—8—9 constituting a bracket which is attached to the cross bar 6 by securing elements 10 passing through the body 7 and holding the body against the cross bar 6, as shown in Figure 2. The numeral 11 designates a brace extended across the angle 12 formed by the parts 8 and 7, the brace 11 having an extension 14 overlapped on the finger 9 of the bracket. A blade 15 is disposed inside of the finger 9 of the bracket. 60 Securing members 16, such as rivets, connect the blade 15, the finger 9 of the bracket, and the extension 14 of the brace 11. The brace 11 is supplied at its inner end with a foot 17 connected by securing devices 70 18 with the body 7 of the bracket. The blade 15, the finger 9, and the extension 14 are disposed in alinement with the ground wheel 3, the blade 15 being spaced as at 19, a little way from the periphery of the wheel 75 3. The result of this construction is that when the ground wheel is running clean, or nearly so, there will be no friction between the ground wheel 3 and the blade 15 of the cleaner; when, however, the wheel 3 balls 80 up a little with mud, the blade 15 will come into operation and clean the wheel down to a thin layer which will do no harm. The blade 15 is held rigidly in place, and is well adapted to withstand the thrust upon it, because it is reinforced by two parts, to wit, 85 the finger 9, and the extension 14. The brace 11 stiffens and reinforces the structure. Owing to the fact that the bracket includes the arm 8 disposed parallel to the wheel 3, the body 7 of the bracket may be attached to the cross bar 6, and, at the same time, the blade 15 may be arranged properly with respect to the periphery of the wheel. The structure is adapted for use on a grain 90 drill of known construction, and works no changes in the grain drill.

What is claimed is:—

In a wheel cleaner, a body provided at one end with an arm located at right angles to the body, the arm terminating in a finger disposed parallel to the body, the body and the finger being spaced apart longitudinally of the arm and projecting in opposite di-

rections, with respect to the arm, at opposite ends of the arm, a brace having an extension which is overlapped on the finger to reinforce it, a blade, securing members connecting the blade, the finger and the extension, the blade and the extension being located on opposite sides of the finger, the

brace being extended across the angle formed by the arm and the body, and means for connecting the brace to the body.

10

In testimony that I claim the foregoing as my own, I have hereto affixed my signature.

HENRY KUNTZ.
